(57) **CLAIM**

I claim the ornamental design for a liquid chess piece, as shown and described.

DESCRIPTION

FIG. 1 is a top front isometric view of a liquid chess piece showing my new design;

FIG. 2 is a bottom front isometric view thereof;

FIG. 3 is a top front isometric exploded view thereof;

FIG. 4 is a bottom front isometric exploded view thereof;

FIG. 5 is a front elevation view, wherein the rear elevation view of the liquid chess piece is a mirror image thereof; and

FIG. 6 is a left side elevation view, wherein the right side elevation view of the liquid chess piece is a mirror image thereof;

FIG. 7 is a top plan view thereof; and,

FIG. 8 is a bottom plan view thereof.

1 Claim, 7 Drawing Sheets
